DESIGN FOR AN ILLUMINABLE STATUE BASE

Margaret Dominick, New Brunswick, N. J.

Application August 8, 1947, Serial No. 140,775

Term of patent 7 years

(Cl. D29—23)

To all whom it may concern:

Be it known that I, Margaret Dominick, a citizen of the United States, residing at New Brunswick, in the county of Middlesex and State of New Jersey, have invented a new, original, and ornamental Design for an Illuminable Statue Base, of which the following is a specification, reference being had to the accompanying drawings, forming a part thereof.

Figure 1 is a front perspective view of an illuminable statue base, showing my new design.

Figure 2 is a back view.

Figure 3 is a top plan view.

The dominant features of my design reside in the portion shown in full lines.

I claim:

The ornamental design for an illuminable statue base, as shown and described.

MARGARET DOMINICK.
